ROCKING CHAIR

Harry A. Gelman and Mac Gelman, Chicago, Ill.

Application May 26, 1950, Serial No. 10,224

Term of patent 14 years

(Cl. D15—6)

To all whom it may concern:

Be it known that we, Harry A. Gelman and Mac Gelman, citizens of the United States, residing at Chicago, in the county of Cook and State of Illinois, have invented a new, original, and ornamental Design for a Rocking Chair, of which the following is a specification, reference being had to the accompanying drawing, forming a part thereof.

Figure 1 is a perspective view of a rocking chair embodying our new design.

Figure 2 is a side elevational view of the rocking chair.

Figure 3 is a front elevational view of the rocking chair.

We claim:

The ornamental design for a rocking chair, substantially as shown.

HARRY A. GELMAN.
MAC GELMAN.
